[57] CLAIM

The ornamental design for a pair of table leg supports, as shown and described.

DESCRIPTION

FIG. 1 is perspective view of a pair of table leg supports, showing my new design, the broken lines are for environmental purposes only and form no part of the claimed design;

FIG. 2 is an end elevational view thereof;

FIG. 3 is an elevational view showing the inside of the legs;

FIG. 4 is a side elevational view, the opposite side being identical thereto;

FIG. 5 is a top plan view thereof;

FIG. 6 is a bottom plan view thereof;

FIG. 7 is an end elevational view, showing an alternate embodiment of my new design;

FIG. 8 is a bottom plan view thereof;

FIG. 9 is a an elevational view, showing the inside of the legs;

FIG. 10 is a top plan view thereof; and,

FIG. 11 is a enlarged fragmentary view showing the central mesh feature in greater detail.
